Primary Examiner — Natasha Vujcic(74) *Attorney, Agent, or Firm* — Buchanan Ingersoll & Rooney PC(57) **CLAIM**

The ornamental design for a mounting device for lighting equipment, as shown and described.

DESCRIPTION

FIG. 1 is a front, right side, top perspective view of a mounting device for lighting equipment showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another front, right side, top perspective view thereof, shown in a position of use.

The broken lines in the drawings illustrate portions of the mounting device for lighting equipment which form no part of the claimed design.
